TOOTHBRUSH HOLDER

Frank E. Neumann, Los Angeles, Calif.

Application June 27, 1949, Serial No. 3,557

Term of patent 14 years

(Cl. D4—3)

To all whom it may concern:

Be it known that I, Frank E. Neumann, a citizen of the United States, residing in the city and county of Los Angeles, and State of California, have invented a new, original, and ornamental Design for a Toothbrush Holder, of which the following is a specification, reference being had to the accompanying drawing, forming part thereof.

Fig. 1 is a side elevation of a toothbrush holder showing my new design.

Fig. 2 is a perspective view showing the toothbrush holder in a separated relation, and

Fig. 3 is a top plan view; a portion of the cap being broken away to disclose the blending of the incurving surfaces of the toothbrush holder.

I claim:

The ornamental design for a toothbrush holder substantially as shown.

FRANK E. NEUMANN.
